UNITED STATES PATENT OFFICE.

CARL JOSEF MITISKA, OF HOWELL, INDIANA.

STOVE.

1,384,772.

Specification of Letters Patent. Patented July 19, 1921.

Original application filed May 21, 1920, Serial No. 383,278. Divided and this application filed January 13, 1921. Serial No. 437,026.

To all whom it may concern:

Be it known that I, CARL J. MITISKA, a citizen of the United States, residing at Howell, in the county of Vanderburg and 5 State of Indiana, have invented a new and useful Stove, of which the following is a specification.

This invention relates to heating stoves, and particularly to an oven for such stoves.

10 The object is to provide a heating stove having an oven for baking or similar purposes placed above the fire in such position as to receive the full amount of heat therefrom without interfering with the passage 15 of the products of combustion up to the flue, said oven having heat regulating means interposed between it and the fire to govern the temperature within the same.

The invention will be best understood 20 from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

Figure 1 is a vertical sectional view through the improved stove.

Fig. 2 is a similar sectional view taken at 35 right angles to Fig. 1.

Fig. 3 is a top plan view partly in horizontal section.

The stove comprises a drum or casing 1 which may be formed of a tubular casting 40 or may be constructed of heavy sheet metal. This drum is supported upon a fire-pot 2 which in turn rests upon a base member 3 preferably rectangular in form. An ash-pit 4 is provided having the usual door 5. 45 The base member 3 is adapted to be supported upon ordinary stove legs 6. A grate 7 is located at the lower part of the fire-pot which may be lined with fire-brick as indicated in dotted lines at 8. All the above 50 is of ordinary construction and may be varied to a considerable extent.

Located a short distance below the top circumferential edge of the drum 1 a permanent head 9 is suitably secured, said head 55 being imperforate and forming a tight clo-

sure for the upper end of the drum. An upstanding tube 10 communicates with the interior of the drum adjacent the rear thereof and extends somewhat above the upper edge of the same, said tube being oval in 60 cross section and provided with a port 11 just above the head 9.

A removable head or cover 12 is adapted to rest upon the upper edge of the drum 1 and is provided with a downwardly-extending flange 13 in surrounding relation to the drum so that it forms a practically air-tight closure therefor. The cover 12 is provided with a corresponding upstanding tube 14 capable of sliding over and surrounding the 70 tube 11 and forming a suitable connection for the smoke pipe 15. The space between the heads 9 and 12 provides an air-distributing chamber 16 into which air may pass as controlled by a damper plate 17, centrally 75 pivoted to a lid 18. The lid has a depending flange fitting within a corresponding opening provided centrally of the cover 12, is readily removable from its seat, and is provided with a series of openings arranged circumferentially around the pivot of the same. These openings are adapted to register with a corresponding series of openings or apertures 19 formed in the damped plate 17. A handle 20 allows ready swinging of the 80 damper plate.

A series of conduits or flues 21 are adapted to be secured to the interior walls of the drum 1 by bolts 22, said flues having their upper open ends communicating with the air 90 distributing chamber 16 and their lower open ends located at the lower end of the drum 1 in close proximity to the upper ends of the fire-bricks. The flues 21 have a series of outlets 23 along their side walls which serve to distribute the heated fresh air directly over the fire.

A bake oven 24, preferably rectangular in cross section, comprising side walls, a top and bottom wall, and a rear wall 25 located 95 in spaced relation to the rear wall of the drum 1, is suitably supported over the fire-pot, a short distance below the permanent head 9. The oven is open at the front of the drum 1, and is adapted to be closed by a suitably hinged door 25^a which may be swung down to form a shelf when open.

Located a short distance below the bottom wall of the oven 24 there is formed a baffle plate 26, preferably integral with the oven 110

and extending to the rear edge thereof. The baffle plate is connected to the bottom of the oven by side walls coextensive therewith, and the space confined between the same 5 constitutes a cold air passage, open at the front and rear ends and controlled by a suitable slide damper 27 of ordinary construction. The rear end of the cold air passage is in spaced relation to the rear wall 10 of the drum so that the air passing therethrough may find ready outlet to intermingle with the heat and pass up the smoke pipe 15.

The fuel feed door 28 is located immediately 15 below the damper 27 in the usual location at the front of the drum 1, and it will be seen the several operable parts are within easy reach.

The port 11, which is open at all times and 20 connects the chamber 16 with the smoke pipe 15 serves, when lighting a fire in the stove, to draw off and up the pipe 15 all smoke and gases which may arise through the conduits 21 and otherwise escape into 25 the room, the draft being sufficient to overcome such tendency.

This application is a division of an application filed May 21, 1920, Serial No. 383,278.

What is claimed is:—

30 1. In a stove, the combination with a fire pot, and a drum supported upon the same, a bake oven carried within the drum above the fire pot and wholly inclosed thereby and in spaced relation with the walls of the 35 drum, said bake oven being provided with a damper-controlled cold air passage open at its inner end and arranged beneath the oven with means to allow cold air to pass between the oven and the fire in order to 40 regulate the effects of the latter upon the oven.

2. In a stove, the combination with a fire pot, and a drum mounted upon the same, a 45 bake oven comprising side walls, top and bottom walls and a rear wall located in spaced relation with the walls of the drum and suitably supported over the fire pot, a baffle plate also supported within the drum below the bottom wall of the oven and in

spaced relation thereto, said baffle plate being connected to said bottom wall at its sides, the space between the baffle plate and the bottom wall of the oven being open at the rear, damper-controlled means for admitting cold air into said space at the front 55 of the stove, and a fuel door provided in the drum below the baffle plate.

3. In a stove, the combination with a fire pot, a drum mounted upon the fire pot, a head spaced from the top of the drum so as to provide an air chamber between said head and the top of the drum, a series of conduits communicating at their upper ends with said chamber and at their lower ends with the interior of the drum, a smoke outlet communicating with and leading from the space below the head, a bake oven carried by the drum in spaced relation to the walls thereof, the rear wall of the bake oven extending to a point beyond the lower opening of the smoke outlet, the top of the bake oven being spaced from said head, and a baffle plate spaced below the bake oven and separated therefrom by an intervening air space.

4. A stove comprising a fire pot, a drum mounted upon the fire pot, an air chamber provided at the top of the drum and of equal area therewith, a damper-controlled air inlet connecting the chamber with the exterior, vertically disposed conduits arranged around the interior walls of the drum and connecting the air chamber with the interior of the drum, said conduits extending down to the fire pot and having a plurality of air outlets in its side walls, and a bake oven carried by the drum over the fire pot and in spaced relation to the walls of the drum, said bake oven being provided with a damper-controlled cold air passage open 90 at its inner end and arranged beneath the oven to allow cold air to pass between the oven and the fire in order to regulate the effects of the latter from the oven.

In testimony that I claim the foregoing as 95 my own I have hereto affixed my signature.

CARL JOSEF MITISKA.
